UNITED STATES PATENT OFFICE.

GEORGE W. MANSON, OF WEST BUXTON, MAINE, ASSIGNOR OF ONE-HALF
TO THOMAS D. HARRISON, OF JERSEY CITY, NEW JERSEY.

SPRING-MOTOR.

SPECIFICATION forming part of Letters Patent No. 340,799, dated April 27, 1886.

Application filed October 9, 1885. Serial No. 179,436. (No model.)

To all whom it may concern:

Be it known that I, GEORGE W. MANSON, of West Buxton, in the county of York and State of Maine, have invented new and useful 5 Improvements in Spring-Motors, of which the following is a specification.

This invention relates to that class of spring-motors which are employed for operating sewing-machines, jewelers' lathes, and similar 10 light-running machines, and in which the power is transmitted from a coiled spring through a train of gearing to the driving-shaft of the machine.

The object of my invention is to provide a 15 simple, compact, and noiseless motor of this character; and the invention consists of the improvements which will be hereinafter described, and pointed out in the claims.

In the accompanying drawings, consisting 20 of two sheets, Figure 1 is a sectional elevation of my improved motor. Fig. 2 is a horizontal section in line $x-x$, Fig. 1. Fig. 3 is a longitudinal sectional elevation in line $y-y$, Fig. 1. Fig. 4 is a detached side elevation of the spring-barrel and alarm device. Fig. 5 is a fragmentary sectional elevation of the brake. Fig. 6 is a cross-section in line $x-x$, Fig. 5. Fig. 7 is a cross-section in line $z-z$, Fig. 3.

Like letters of reference refer to like parts 30 in the several figures.

A represents the table, and A' a portion of the frame of a sewing-machine supported thereon.

a represents the driving-shaft of the machine, 35 supported in bearings in the frame A', and provided with the usual driving pulley, a', and fly-wheel a'.

B B' B² represent the hangers or frames of the motor, which are secured to the under side 40 of the table A and connected at their lower ends by brace-rods b.

C represents a horizontal shaft journaled in bearings in the frames B B', and C' represents a drum or barrel, which is mounted 45 loosely on the shaft C and incloses a coiled spring, D. The barrel C' is preferably cast in two parts, c c', which are secured together by screws or bolts c'', inserted through lugs c', formed on the adjacent sides of the parts c c'. 50 The outer end of the spring D is secured to the barrel C' by a nut, d, and its opposite end

is connected to the shaft C by means of a sleeve or collar, d', the latter being held from turning on the shaft C by a key, d''.

E represents a screw or worm-wheel formed 55 on or secured to a shaft, e, which is journaled in bearings e', formed on the frame B. The worm-wheel E engages with a gear-wheel, E', keyed or otherwise secured to the shaft C.

e' is a hand-crank, whereby the worm-wheel 60 E and gear-wheel E' are turned to wind the spring D upon the shaft C. The wheel E' is held from turning backwardly by the worm E.

F represents a toothed wheel mounted on 65 an arbor, f, secured to one side of the barrel C', and f' is a tooth or projection formed on or secured to the shaft C, and engaging between the teeth on the wheel F in such manner that the wheel F is moved the distance of 70 one tooth at every revolution of the shaft C.

G represents an alarm-bell secured to the 75 side of the barrel C', and g is a spring-hammer, which is adapted to come in contact with a pin or stop, g', on the wheel F as the latter revolves. The stop g' is so arranged on the wheel F as to cause the hammer g to strike the bell and sound an alarm when the spring D has been sufficiently wound.

H represents a gear-wheel, which is secured 80 to the opposite side of the spring-barrel C' by screws h, so as to revolve with the barrel.

i i' i'' represent short shafts or spindles journaled in bearings in the frames B' B².

I I' I² represent gear-wheels, and J J' J² are 85 spur-pinions secured, respectively, to the shafts i i' i''. The gear-wheel H, secured to the spring-barrel C', meshes with the pinion J on the shaft i, and the gear-wheel I on the shaft i with the pinion J' on the shaft i', and the gear-wheel I' on the shaft i' with the pinion J² on the shaft i'', whereby motion is transmitted from the spring-barrel C' to the shaft i through the gear-wheel H and pinion J, and from the shaft i to the shaft i' through the gear-wheel I and pinion J', and from the shaft i' to the shaft i'' by means of the gear-wheel I' 90 and pinion J².

K is a counter-shaft journaled in bearings 95 formed in the hanging frames B B' B² and provided with a pinion, k, which meshes with the gear-wheel I² on the shaft i'', whereby motion is transmitted from the shaft i'' to the shaft K.

The shaft K is provided with a belt-pulley, L, which is connected with the driving-pulley a' of the sewing-machine by a belt, l. Motion is in this manner transmitted from the spring D 5 through the train of gearing to the driving-shaft of the sewing-machine.

M represents a brake-pulley secured to the shaft K so as to turn therewith.

N represents the brake-rod, which is provided at its lower end with a horizontal pressure-finger, n, which is adapted to bear against the brake-pulley M and stop the motion of the machine. The brake-rod N is guided near its lower end by a pin or screw, o, secured to the 15 frame B' and passing through a slot, o', formed in the brake-rod. The upper end of the rod N extends through an opening in the table A, and is pivoted to the short arm p of a hand-lever, P, which latter is pivoted to a vertical 20 post, q, secured to the top of the table A.

r is a flat or other suitable spring secured to the frame B' and bearing against the brake-rod N, whereby the pressure-finger n is forced against the brake-wheel. Upon pressing down 25 upon the long arm p' of the hand-lever P the rod N is raised until the horizontal portion n' of the finger n is forced against the inner face of the rim of the brake-wheel, whereby the motion of the machine is arrested. When the 30 brake is thus applied, the spring-barrel C' is held from turning through the gear-wheel H and train of gearing communicating with the shaft of the brake-wheel.

When it is desired to wind up the spring D, 35 the brake is applied and the shaft C revolved, by means of the hand-crank e² and worm-gear E E', until the stop g' comes in contact with the hammer g and causes the latter to strike the bell and sound the alarm, when the operator is informed that the spring has been 40 wound sufficiently tight. The arm p' of the hand-lever is now raised, so as to release the brake, when the pressure of the spring D upon the barrel C' will cause the latter to 45 revolve and set the train of gearing in motion. The shaft C is held at rest by the worm-gear E E'.

If desired, the spring may be wound upon the shaft C while the machine is in motion by 50 turning the hand-crank e².

The worm-wheel may be made right or left handed, to suit the different styles of machines to which the motor is applied.

When it is desired to regulate the speed of 55 the machine, the brake-rod N is raised sufficiently to permit the spring r to press the side

of the finger against the face of the brake-wheel without touching the rim of the wheel.

My improved motor is simple in construction and is entirely noiseless, and can be 60 readily applied to any sewing-machine or other light-running machines where light power is required.

I claim as my invention—

1. In a spring-motor, the combination, with 65 the shaft C, and the drum C', mounted loosely on said shaft, of a spring, D, connected at one end to the drum C' and at its opposite end to the shaft C, a gear-wheel, E', secured to the shaft C, and a worm-wheel, E, engaging with the 70 gear-wheel E', substantially as set forth.

2. In a spring-motor, the combination, with the shaft C, and the drum C', mounted loosely on said shaft, of the spring D, inclosed in said drum and secured at its opposite ends to the 75 shaft C and drum C', a gear-wheel, E', secured to the shaft C, a worm-wheel, E, engaging with the gear-wheel E', and an alarm device secured to the drum C' and operated by the shaft C, substantially as set forth. 80

3. In a spring-motor, the combination, with the shaft C and the spring D, secured thereto, of a drum, C', mounted loosely on the shaft C, a gear-wheel, E', secured to the shaft C and engaging with a worm-wheel, E, a bell, G, 85 spring-hammer g, toothed wheel F, stop g', and tooth f, substantially as set forth.

4. In a spring-motor, the combination, with the shaft C, spring D, and the drum C', inclosing said spring and mounted loosely on 90 the shaft C, of the gear-wheel E', secured to the shaft C and engaging with a worm-wheel E, a gear-wheel, H, secured to the drum C', a shaft, K, provided with a pinion, k, and a train of gear-wheels, I I' I², and pinions J J' J², whereby 95 motion is transmitted from the drum C' to the shaft K, substantially as set forth.

5. In a spring motor, the combination, with the shaft C, spring D, and drum C', of the gear-wheel H, secured to said drum, shaft K, 100 provided with a pinion, k, gear-wheels I I' I², and pinions J J' J², forming a communication between the drum C' and shaft K, a brake-wheel, M, secured to the shaft K, and a brake-arm, N, provided with a pressure-finger, n, substantially as set forth. 105

Witness my hand this 22d day of September, 1885.

GEORGE W. MANSON.
